UNITED STATES PATENT OFFICE.

ARTHUR BERTRAM COLEMAN, OF GOSNELLS, NEAR PERTH, AUSTRALIA.

CARPENTER'S HAMMER.

1,425,369.

Specification of Letters Patent. Patented Aug. 8, 1922.

Application filed November 22, 1920. Serial No. 425,826.

To all whom it may concern:

Be it known that I, ARTHUR BERTRAM COLEMAN, a subject of the King of Great Britain, residing at Wheatley Street, Gosnells, near Perth, Western Australia, Commonwealth of Australia, have invented certain new and useful Improvements in Carpenters' Hammers, of which the following is a specification.

- 10 This invention relates to carpenters' hammers and its object is to provide integral structural means whereby said hammers are enabled to fully and totally effect the extraction of nails without the aid of separate or 15 auxiliary fulcrums as is now the present practice with the existing type of a single clawed hammer. This invention consists in integrally forming the hammer with a multiple or a plurality of pairs of claws which 20 are nested and arranged in a stepped manner beneath and at the rear of the ordinary and primary pair of claws thus providing structural means for effecting the total extraction of nails at their extreme projective 25 lengths by successively engaging the head of the nail with the repetitional or plurality of claws. By the use of this invention the nail is not bent or otherwise injured by or during the extraction action 30 hence one economic advantage of the invention consists in economy of nails as the nails when extracted by this invention are fit for further use. A further advantage of this invention resides in that the hammer 35 is enabled to be operated close up to the nail thus reducing the unit of movement of the hammer during the process of the nail extraction. The invention will now be explained with the aid of the attached drawings 40 wherein Fig. 1— is a perspective view showing a hammer made in accord with my invention. Fig. 2— is a view in elevation showing the hammer in its operative position at the final extraction of the nail and in 45 said position the nail maintains its straight vertical position.

Referring to said drawings the hammer as *a* is integrally formed with a multiple or plurality of rearwardly extending pairs of claws as *b*— *c*— and *d* preferably of the shape and design as shown and which pairs of claws are arranged in a stepped manner

and they rearwardly extend from the ordinary or primary pair of claws as *e*. The pairs of claws *b* *c* and *d* vary in angular disposition from the primary claws *e* to the rearmost pair of claws *d*, and the grooves between these pairs of supplemental claws increase in depth from the minimum grooved claws *b* to the deeper grooved claws *d*.

These claws extend from their tips to their common root line or groove as *f* and wherein and whereat the head of the nail as *x* is gripped. In Fig. 2— the nail *x* is shown as being gripped by the rear pair of claws as *d* and which claws *d* effect the final or total extraction of the nail and it will be clearly seen therefrom that said nail *x* maintains its true vertical and straight position at and during its final extraction and is withdrawn in an uninjured condition.

It will be further seen that the hammer at such final position of extraction is close up to its work on the nail and only requires to be brought to approximately its vertical position to effect such total extraction of the nail thus requiring a short unit of movement in contradistinction to the present necessary long unit of movement with hammers of the present type of construction.

What I claim as my invention and desire to secure by Letters Patent is—

A hammer having the usual primary nail drawing claws projecting from the end thereof and also formed with a plurality of rearwardly extending supplemental pairs of claws arranged in stepped disposition and having nail grooves therein increasing in depth from the minimum depth in the pair of claws adjacent to the usual claws to the maximum depth of the groove in the rearmost pair of claws, whereby the extraction of nails is effected by engagement of each nail throughout its length to obviate bending of the nail during extraction.

In testimony whereof I have hereunto set my hand in presence of two subscribing witnesses.

ARTHUR BERTRAM COLEMAN.

Witnesses:

RICHARD SPARROW,
FRED H. LAMBERT.
